UNITED STATES PATENT OFFICE.

HENRY GEORGE RUSH, OF OIL CITY, PENNSYLVANIA.

GAS-BURNER FOR FIRING BARRELS.

SPECIFICATION forming part of Letters Patent No. 699,578, dated May 6, 1902.

Application filed December 7, 1901. Serial No. 85,057. (No model.)

To all whom it may concern:

Be it known that I, HENRY GEORGE RUSH, a citizen of the United States, residing at Oil City, in the county of Venango and State of Pennsylvania, have invented a new and useful Barrel-Heater, of which the following is a specification.

The present invention relates to heaters for barrels and the like; and the object thereof, broadly, is to provide a simple apparatus of this character by means of which barrels may be thoroughly fired without leaving an undesirable residue upon the same and without inconvenience of smoke and noxious gases.

15 A very important feature of the invention relates to the use of a burner and automatic means whereby fuel will be supplied to the burner only when a barrel is placed in position to be fired, thus effecting a great saving 20 in fuel.

Other important features relate to the specific construction of burner and to a novel form of deflector by means of which the heat will be distributed and deflected equally to 25 all parts of the interior of the barrel being operated upon.

The preferred embodiment of the invention is fully illustrated in the accompanying drawings and described in the following specification, 30 although such changes may be made from the construction set forth as the scope of the appended claims will permit.

In said drawings, Figure 1 is a vertical sectional view through the apparatus, showing a 35 barrel in place thereon. Fig. 2 is a top plan view of the barrel support or base. Fig. 3 is a vertical longitudinal sectional view through the same. Fig. 4 is a similar view taken at right angles to Fig. 3. Fig. 5 is a side elevation of the burner-head. Fig. 6 is a top plan view of the covering, and Fig. 7 is a detail view of the actuating-arm.

Similar numerals of reference designate corresponding parts in all the figures of the drawings.

45 In carrying out the invention a barrel-support is provided consisting, preferably, of a rectangular base-plate 10, having a circular depressed barrel-seat 11, which seat is provided with a central opening 12, through which projects the end of a mixer-tube 13. This mixer-tube constitutes a part of a gas-

burner the head 14 of which is secured to the projecting end of said tube, being constructed substantially as follows: An outer conical 55 wall 15 is attached at its apex to the end of the mixer-tube, the larger or flaring end being uppermost, and to this larger end is secured an inner conical wall 16, somewhat smaller than the outer wall, thereby forming 60 between the two a gas-chamber 16^a. The outer wall is provided with a plurality of escape-apertures 17, and its outer surface is preferably protected by a covering of asbestos 18 or other similar heat-resisting material. 65 The gas-supply pipe 19 leads to the mixer-tube, which tube is provided with suitable air-inlets 20. The passage-way through the supply-pipe is controlled by a valve 21, which may be of any desirable or well-known construction, being so made that it will close when 70 there is no pressure exerted against it.

A groove 22 is formed in the bottom of the barrel-seat 11, said groove extending from near its center to the edge of the platform, 75 and in the same is located an actuating-arm 23, hinged, as at 24, to the platform at the inner end of the groove. The outer end of said arm is provided with an eye 25, in which is attached one end of a link 26, the other end 80 of said link being secured to a lever 27, which actuates the valve, as will be readily understood.

A deflector 28 is employed for the barrel while being operated upon, and it consists of 85 a pair of facing-plates 29, spaced apart by blocks 30 and connected by tie-bolts 31, said tie-bolts serving as fastening devices for outwardly-extending supporting-hooks 32, fixed upon the outer face of the upper plate. A 90 handle 33 may be employed for lifting and carrying the cover. This deflector is so constructed that when in place upon a barrel, as shown in Fig. 1, its edges will be spaced a slight distance from the inner face of said 95 barrel, so as to permit the escape of the heated products of combustion.

The operation of the apparatus will be apparent. Under normal conditions or when there is no barrel being operated upon the 100 arm 23 will be in substantially the position shown in Fig. 3—namely, above the groove in which it operates—and the valve 21 will be either entirely or partially closed, so that

only sufficient gas will pass therethrough to keep a flame at the burner-head. When, however, a barrel is placed upon the platform, said burner-head will be centrally positioned with respect to the barrel when the latter is placed in the circular seat 11, and coming into contact with the arm 23 its weight will depress said arm, thereby throwing the valve 21 to open position and allowing the gas to flow through the mixer-tube and into the burner-head. It will escape on all sides of said head, and thus a flame will be provided equidistant from the interior faces of the barrel. The upwardly and outwardly flaring arrangement of the head deflects the heat toward the walls, and this deflection is furthermore assisted by the deflector, which is of course placed in position directly after the barrel has been seated in place.

By the employment of gas there will be no undesirable residue left upon the barrel and no smoke or noxious gases. Furthermore, because of the automatic actuating mechanism for the valve 21 a great saving in fuel is effected. The specific structure of the burner is advantageous, as it constitutes a deflector for throwing the heat against the walls of the barrel; but it is to be understood that the invention is not to be limited to the specific structure of the same, as other forms may be employed, if desired.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim as new, and desire to secure by Letters Patent, is—

1. In a barrel-heating apparatus, the combination with a barrel-support, of a burner projecting above the support and located within a barrel placed upon said support, a supply-pipe leading to the burner, a valve controlling the passage-way through the pipe, and operating means for the valve connected thereto and normally projecting above the barrel-support, said means being engaged and moved by a barrel when placed upon said support.

2. In barrel-heating apparatus, the combination with a barrel-supporting platform, of a burner arranged above the platform and located within a barrel placed on said platform, a supply-pipe leading to the burner, a valve controlling the passage-way through the pipe, and a valve-operating arm extending across the platform and having a connection with the valve, said arm being moved by a barrel when placed upon the platform.

3. In barrel-heating apparatus, the combination with a barrel-support, of a burner, a

supply-pipe leading to the burner, a valve controlling the passage-way through the pipe, and a valve-operating arm hinged at one end to the support and extending across the upper face of the same, said arm having a connection at its free end with the valve, and being moved by a barrel placed upon the platform.

4. In barrel-heating apparatus, the combination with a barrel-support having a groove, of a burner projecting above the platform and having a valve, and an operating-arm for the valve connected thereto and located at one end of and below the burner, said arm being movable in the groove of the support.

5. In barrel-heating apparatus, the combination with a platform having a depressed barrel-seat, said seat being provided with a groove, of a burner, a valve for the burner, and an operating-arm for the valve pivoted to the platform at the inner end of the groove and located in the groove of the seat, said arm being connected at its outer end to the valve.

6. In barrel-heating apparatus, the combination with a barrel-supporting platform, of a burner located upon the platform, said burner comprising a body that tapers toward its lower end and having openings in its side walls, said body constituting a deflector to throw the heat against the sides of a barrel placed thereover.

7. In barrel-heating apparatus, the combination with a barrel-support and burner, of a cover for the barrel comprising spaced facing-plates, and barrel-engaging devices for supporting the plates in spaced relation to the barrel-walls to permit the escape of the products of combustion.

8. In barrel-heating apparatus, the combination with a barrel-support, of a burner, a deflector for the barrel comprising spaced facing-plates, and upwardly and outwardly projecting barrel-engaging hooks secured to one of the plates.

9. In barrel-heating apparatus, the combination with a barrel-supporting platform, of a burner located thereon and disposed within a barrel placed upon the platform, and a deflector arranged to be supported within the barrel and spaced from the walls thereof to allow the heat to escape only about the edges of said cover.

10. In barrel-heating apparatus, the combination with a barrel-supporting platform, of a burner comprising inner and outer conical walls spaced from each other and secured together at their outer peripheral edges, the inner conical wall being open at its base, and a deflector arranged to be supported within a barrel in spaced relation to the walls thereof.

11. In a barrel-heating apparatus, the combination with a barrel-supporting platform, of a burner located upon the platform and comprising inner and outer conical walls spaced apart from each other and secured together at their outer peripheral edges, said edges being arranged uppermost, and the inner conical wall being open at its base.

12. In a barrel-heating apparatus, the com-

5 bination with a barrel-support, of a burner located upon an intermediate portion of the support, barrel-positioning means arranged upon the support in spaced relation to the burner, a controlling-valve for the burner, and actuating means for the valve connected thereto and arranged contiguous to the barrel-positioning means, whereby said actuating means will be moved by a barrel placed

upon the support and in coacting relation with 10 the positioning means.

In testimony that I claim the foregoing as my own I have hereto affixed my signature in the presence of two witnesses.

HENRY GEORGE RUSH.
